RING ASSEMBLY

Elmer R. Stahl, Meyersdale, Pa., assignor to Celanese Corporation of America, a corporation of Delaware

Application February 16, 1940, Serial No. 319,259

6 Claims. (Cl. 57—120)

This invention relates to a ring assembly and relates more particularly to an improved positive-lubricating ring assembly for use in the high speed spinning and twisting of yarn.

5 An object of my invention is the provision of a novel spinning ring assembly provided with means for uniformly lubricating the surface upon which the moving traveler bears.

10 A further object of my invention is to provide an improved lubricating means for a spinning ring assembly in which the supply of lubricant to the bearing surface is so controlled that neither loss of lubricant nor soiling of the yarn will occur.

15 Another object of my invention is to so locate said lubricant supply that any excess of lubricant upon the above-mentioned bearing surface will be caught and returned to the main oil supply.

20 Still another object of my invention is to provide a spinning ring construction which is adapted to increase the speed at which ring spinning and twisting devices may operate, thereby increasing the production of yarn.

25 Other objects of my invention will appear from the following detailed description of the invention.

In the accompanying drawing, wherein the preferred embodiment of my invention is shown,

30 Fig. 1 is a plan view of the ring assembly,

Fig. 2 is a vertical elevation of the ring assembly,

35 Fig. 3 is an enlarged cross-sectional view of the lubricating mechanism and is taken on the line 3—3 of Fig. 1, and

Fig. 4 is a cross-sectional view of the ring with the traveler in position.

Like reference numerals indicate like parts throughout the several views of the drawing.

40 Referring specifically to the drawing, there is shown a spinning ring assembly, generally indicated by the reference numeral 5, which comprises a bottom section 6 having integral bifurcated brackets 7 which are adapted to be attached to the ring rail, a top section 8 seated on and fixed to said bottom section as by means of screws 9 and a spinning ring 10 which is held in position by means of said top section as

45 is well understood in the art. It is to be understood that the top section 8 and the ring 10 may be fabricated as a single piece. Said ring 10

50 may be any type of spinning ring adapted to be lubricated. The tapered bore ring shown is merely illustrative.

A reservoir 11 which holds the main oil supply is formed integral with the inner periphery of the bottom section 6. In order that this main body of oil is not unduly disturbed by any air currents created by the flanges of and/or the 5 yarn package on the spindle mechanism revolving at high speed in close proximity thereto, a suitable baffle 12 of any suitable material which may be inclined toward the body of the oil is supported by a lip 13, said lip 13 being integral 10 with the upper free edge of the reservoir. This lip 13 and baffle 12 are so positioned that any oil dripping from the lower edge of the ring 10 will be caught by the said lip and the surface of 15 the baffle and returned to the reservoir. It is obvious, however, that other means may be utilized to serve as a baffle to prevent the main body of oil being unduly disturbed.

The oil from reservoir 11 is drawn therefrom and forced toward the bearing surface 14 of 20 spinning ring 10 by a piston 15 which is journaled in sleeve 16. The piston, when pressed downward, exerts a pressure and forces the oil out of the space or cylinder 17 into which it had previously been drawn by an upstroke of said 25 piston, through the connecting duct 18, past the ball check valve 19, into the oil duct 20 and then into a distributing manifold or header 21. The distributing manifold 21 is an annular or 30 sectional space formed at the junction of the top section 8 and the rear portion 22 of the ring 10. Manifold 21 is annular or sectional in form and may or may not extend along the full circumference of the spinning ring 10. Connected to said manifold are the wick holes 23 which 35 supply the oil from said manifold to annular or sectional groove 24 which is situated at the upper edge of the bearing surface 14 and thence by gravity to the bearing surface 14 of the spinning ring. The manifold 21 and/or the wick 40 holes 23 are filled with wicking or other porous material to prevent the oil from spouting and to give a uniform flow of oil to the oil groove 24 and down over the bearing surface 14. This construction causes the oil to be properly distributed to the bearing surface 14 and to lubricate 45 said surface and the moving traveler 25 bearing thereon as shown in Fig. 4.

When the piston 15 is released after the downward stroke it is forced back to the top of the 50 stroke by a spring 26 bearing on the extension 27 which may be integral with the top of the piston. The length of stroke of the piston may be adjusted by the screw 28. The release of the piston creates a suction which unseats a 55

ball check valve 29 while firmly seating ball check valve 19. This suction draws oil from the reservoir 11 through the connecting oil duct 30 and past the check valve 29 and at the same time 5 forces the oil into the connecting oil duct 18 and the cylinder 17.

On the downward stroke of the piston the ball check valve 29 is seated, check valve 19 is unseated and the oil passes upward and outward 10 through oil duct 20 into the manifold 21, is then distributed to the wick holes 23 and thence to the oil groove 24 and to the bearing surface 14.

In conjunction with the oil ducts there may be an air cylinder 31 located directly over the 15 enlarged section of the oil duct containing the ball check valve 19. The purpose of this air cylinder is to provide a cushion of air to absorb the transmitted shock of the downward stroke of the piston 15 and to slow or control the flow 20 of oil to the oil groove 24.

The piston is preferably located towards the back edge of the ring rail and is actuated at each upward stroke of the ring rail which causes extension 27 to come into contact with a stationary 25 arm (not shown) suitably positioned on the machine frame in the path of said piston. It is obvious, however, that other means may be utilized for actuating the piston since any other movement which regularly or intermittently depresses the piston will force the lubricant through 30 the connecting ducts and out on to the bearing surface 14.

If desired, an external orifice or well with a connecting duct to the reservoir 11 may be provided for the indication of the level of oil in said 35 reservoir 11. Suitable means for replenishing the supply of oil when necessary may be provided in connection with said well and duct.

The mechanism herein described for the automatic lubrication of the traveler bearing surface 40 permits yarn to be wound and twisted with higher traveler speeds than have heretofore been possible. Although traveler speeds may be raised there is no noticeable increase in wear on the traveler 45 or in breaking of ends, nor is there any reduction in the uniformity and quality of the yarn.

It is to be understood that the foregoing detailed description and drawing are given merely by way of illustration and that many variations 50 may be made therein without departing from the spirit of my invention.

Having described my invention, what I desire to secure by Letters Patent is:

1. The combination with a ring rail for a ring 55 spinning machine of a plunger pump for supplying lubricant to the inner surface of a ring of said rail and a reservoir feeding said pump, said pump and reservoir being so positioned as to move with the rail, the reservoir being beneath the ring so as to collect any excess oil supplied thereto and the pump being adapted to be operated by the reciprocating movement of the ring rail.

2. The combination with a ring rail for a ring 60 spinning machine of a plunger pump for supplying lubricant to the inner surface of a ring of said rail and a reservoir feeding said pump, said pump and reservoir being so positioned as to move with the rail, the reservoir being beneath the ring so as to collect any excess oil supplied thereto 65 and the pump comprising a block rigidly attached to the rail and provided with a vertical bore, a plunger in said bore adapted to be depressed by contact with a fixed stop during each upward stroke of the rail and to be raised by a spring 70 during each downward stroke of the rail, and

inlet and outlet passages from the bore below the piston, the inlet passage communicating with the reservoir, and the outlet passage adapted to supply the inner surface of the ring, and non-return valves for controlling the flow in said 5 passages.

3. The combination with a ring rail for a ring spinning machine of a plunger pump for supplying lubricant to the inner surface of a ring of said rail and a reservoir feeding said pump, said 10 pump and reservoir being so positioned as to move with the rail, the reservoir being beneath the ring so as to collect any excess oil supplied thereto, the pump comprising a block rigidly attached to the rail and provided with a vertical 15 bore, a plunger in said bore adapted to be depressed by contact with a fixed stop during each upward stroke of the rail and to be raised by a spring during each downward stroke of the rail, and inlet and outlet passages from the bore below 20 the piston, the inlet passage communicating with the reservoir, and the outlet passage adapted to supply the inner surface of the ring, and non-return valves for controlling the flow in said 25 passages, a guide member rigidly attached to the plunger, a vertical guide rod for said member, said rod being screwed into said block so as to be adjustable as to height, and a flange at the upper end of said rod adapted to limit the upward movement of the guide member along the 30 rod.

4. The combination with a ring rail for a ring spinning machine of a plunger pump for supplying lubricant to the inner surface of a ring of said rail and a reservoir feeding said pump, said 35 pump and reservoir being so positioned as to move with the rail, the reservoir being beneath the ring so as to collect any excess oil supplied thereto and being provided with a sloping plate adapted to shield the oil in the reservoir from the draught caused by the spindle and at the same time to provide a sloping path for excess oil into the reservoir and the pump being adapted to be operated by the reciprocating movement of the ring rail.

5. The combination with a ring rail for a ring spinning machine of a plunger pump for supplying lubricant to the inner surface of a ring of said rail and a reservoir feeding said pump, said pump and reservoir being so positioned as to move with the rail, the reservoir being beneath the ring so as to collect any excess oil supplied thereto and being provided with a sloping plate adapted to shield the oil in the reservoir from the draught caused by the spindle and at the same time to provide a sloping path for excess oil into the reservoir, the pump comprising a block rigidly attached to the rail and provided with a vertical bore, a plunger in said bore adapted to be depressed by contact with a fixed stop during each 40 upward stroke of the rail and to be raised by a spring during each downward stroke of the rail, and inlet and outlet passages from the bore below the piston, the inlet passage communicating with the reservoir, and the outlet passage adapted 45 to supply the inner surface of the ring, and non-return valves for controlling the flow in said passages, a guide member rigidly attached to the plunger, a vertical guide rod for said member, said rod being screwed into said block so as to be 50 adjustable as to height, and a flange at the upper end of said rod adapted to limit the upward movement of the guide member along the rod.

6. The combination with a ring rail having a plurality of rings for a ring spinning machine of 75

a plurality of plunger pumps for supplying lubricants to the inner surface of the rings of said rails and a plurality of reservoirs feeding said pumps, said pumps and reservoirs being so positioned as to move with the rails, the reservoirs being beneath the ring so as to collect any excess

oil supplied thereto and the pump being adapted to be operated by the reciprocating movement of the ring rail, there being one pump and one reservoir for each ring.

ELMER R. STAHL. 5
